WILLIAM LIPPS, OF SHELBYVILLE, INDIANA, ASSIGNOR OF ONE-HALF TO DANIEL DE PREZ,
OF SHELBYVILLE, INDIANA.

DUPLEX SASH-LOCK.

No. 909,482

Specification of Letters Patent.

Patented Jan. 12, 1909.

Application filed September 26, 1908. Serial No. 454,857.

To all whom it may concern:

Be it known that I, WILLIAM LIPPS, a citizen of the United States, residing at Shelbyville, in the county of Shelby and State of Indiana, have invented certain new and useful Improvements in Duplex Sash-Locks; and I do declare the following to be a full, clear, and exact description of the invention, reference being had to the accompanying drawings, and to the figures of reference marked thereon, which form a part of this specification.

This invention relates to locks for vertically sliding window sashes and to the class adapted to lock both the upper sash and the lower sash in any desired position independently either when open more or less or in closed positions, and so that the sashes will be secured to the window frame.

The object of the invention is to provide an improved duplex sash lock that will be very strong and yet adapted to be of light weight and cheaply constructed, and which will not be liable to get out of order when in use.

With the above mentioned and other objects in view the invention consists in an improved duplex sash lock having novel forms of lock bolts and guides therefor and having also novel devices for withdrawing the lock-bolts; and the invention consists further in parts, and combinations and arrangements of parts, as hereinafter particularly described and defined in the accompanying claims.

Referring to the drawings, Figure 1 is a fragmentary front elevation of a window-frame and a pair of sashes to which the improved sash lock is applied; Fig. 2, a front elevation of the lock minus the front plate thereof and partially broken away; Fig. 3, a transverse sectional view of the complete lock at the plane of the line A A in Fig. 2; Fig. 4, a transverse sectional view of the complete lock at the plane of the line B B in Fig. 45 2; Fig. 5, a fragmentary sectional elevation approximately on the line C C in Fig. 1, and broken away at different planes to expose the sash lock; Fig. 6, a side view of the key whereby the lock may be operated; Fig. 7, a horizontal sectional view of the complete lock on the line D D in Fig. 2; Fig. 8, a fragmentary horizontal sectional view approximately on the line E E in Fig. 5; Fig. 9, a longitudinal sectional view of one of the lock bolt guides;

and, Fig. 10, a perspective view of one of the lock bolts.

Similar reference characters throughout the drawings indicate like elements or features of construction referred to herein.

The improved sash-lock comprises a lock case preferably formed of sheet metal and comprising a back 1; a top 2 and a bottom 3 formed integral with the back, and ends 4 and 5 also formed integral with the back, the ends having projections 4' and 5' respectively; a front 6 secured to the top and bottom and also to the ends by means of said projections, the front having projections 6' and 6'' by which the lock case is secured by means of screws 7 and 7'. The case is box-shaped and designed to be set into the window frame, so as to be hidden by the sashes. In one end portion of the case is a lock-bolt guide 8, and a similar guide 8' is arranged in the opposite end portion of the case, the guides being preferably formed of sheet metal rolled into tubular form and having projections 9 and 9' whereby they are secured to the back 1 of the case, the guides extending through suitable openings in the front 6 of the case, so that the guides are firmly supported. Each guide has two oppositely disposed slots 10 in the wall thereof extending longitudinally, and the outer ends of the slots serve as stop-shoulders for limiting the outward movements of the lock-bolts 11 and 11' which are mounted slidably in the guides, one to a guide, one lock-bolt having lateral projections 12 and the other lock-bolt having similar projections 12', the projections extending through the slots. A coil spring 13 extends about the guide 8 and is seated against the back 1 and engages the projections 12; a spring 13' extends about the guide 8' and being seated against the back 1 engages the projections 12', the springs normally forcing the lock-bolts outward to operative positions with the projections engaging the stop-shoulders. In this construction as will be seen the lock-bolts have considerable length and relatively long guides are provided for the lock-bolts, and also relatively long springs are used, so as to be durable.

A rock-shaft 14 is suitably journaled at its ends in the ends 4 and 5 of the case, and one end thereof has a bore 15 and two longitudinal slots 16 and 16' extending from the bore through the wall of the rock-shaft which, as

is apparent, is hollow at one end thereof. A collar 17 is placed on the rock-shaft and is secured thereto by a pin 18, the collar having projections 19 and 19' extending to the inner sides of the ends 4 and 5 of the case and preventing the rock-shaft from longitudinal movement. The collar has two integral fingers 20 and 20' that engage the projections 12 and 12' for withdrawing the lock-bolts, the fingers being arranged between the projections and the front 6 of the case. A plate spring 21 is suitably secured to the back 1 and extends over the rock-shaft 14 and near the end 5 of the case, the spring having a projection 22 at the underside of its end to be engaged by a key which comprises a cylinder 23 having a pair of wings 24 and 24' thereon, the cylinder having a shank 25 on which is a handle 26. The cylinder 23 may be inserted 20 in the bore 15 with the wings 24 and 24' in the slots 16 and 16' which will enable the key to turn the rock-shaft until the uppermost one of the wings passes under the projection 22 and is caught thereby to be held under ordinary conditions, and by turning the key forcibly in reverse direction, the wing may be forced from under the projection, so as to again permit the withdrawn lock-bolts to advance outward to normal positions. The proper position in which the lock should be placed is in a mortise in the frame 27 of the window with the face of the front 6 flush with the front face of the frame parts against which the sashes are designed to slide.

In the drawings, 28 indicates the facing that is attached to the frame 27 and preferably a tube 29 is inserted in the frame and facing for guiding the key to the sash-lock, and escutcheon 30 being attached to the facing 28 at the outer end of the guide tube 29. The dividing strip 31 between the sashes is cut away to permit the lock to be readily removed if desired, and the guide strip 32 is of the usual form, 33 indicating the lower sash and 34 the upper rail thereof; 35 indicating the upper sash and 36 the lower rail thereof. The sashes are preferably provided with perforated metal plates 37 and 38 arranged opposite to the lock-bolts 8 and 8', 50 as has heretofore been the practice.

In practical use the key is inserted through the guide tube 29 and into the hollow end of the rock-shaft, after which the key may be turned slightly toward the right until caught by the projection 22, thus unlocking both sashes, and then either one or both sashes may be moved to approximately the desired positions, after which the key may be turned in reverse direction, or the key may 60 be withdrawn until the wing becomes disengaged from the projection 22 and then the key may be slightly turned and withdrawn, the result in either case being that the springs 13 and 13' will project the lock-bolts 65 against the sashes or the plates 37 and 38.

Then by moving the sashes slightly the lock-bolts will enter the perforations in the plates, or the sashes. Of course, if one of the sashes is not shifted one lock-bolt will return to its former position in such sash.

70

Having thus described the invention, what is claimed as new, is—

1. A sash lock comprising a case having a back and a front, a tubular guide secured to the back and extending through the front of the case, the guide having two longitudinal slots in its wall, a lock-bolt movable longitudinally in the guide and having two projections thereon extending through the slots, a spring on the guide seated against said back and also against said projections, a rock-shaft mounted in the case, and a finger on the rock-shaft engaging one of said projections.

2. A sash lock comprising a case having a back and two ends, a lock-bolt mounted movably in the case and having a projection thereon, a spring seated against the back and also against the projection, a rock-shaft mounted in the ends and having a bore in one end thereof and slots at the sides of the bore, a finger on the rock-shaft engaging said projection, a key to enter said bore and having wings to enter said slots to turn the rock-shaft, and a spring secured to said back and extending over the rock-shaft, said spring having a projection thereon to be engaged by one of said wings.

3. A duplex sash lock comprising a case having a back and a front and also two ends, two tubular guides secured to said back and extending through said front, each guide having two longitudinal slots in its wall, two lock-bolts movable longitudinally in the guides, one in each guide, each lock-bolt having two projections that extend through the slots in the guide, two springs coiled about the guides, one on each guide, and seated against said back and also against the projections that extend through said slots, 100 said springs normally holding said projections in contact with said walls at the outer ends of said slots, a rock-shaft mounted in said case ends and having a bore and also slots in one end thereof to receive a wing-key, 105 a spring secured to said back and having a projection thereon to be engaged by a wing of the key, a collar on the rock-shaft and having two projections thereon engaging said case ends, a pin securing said collar to said 110 rock-shaft, and two fingers on said collar and engaging projections on said lock-bolts.

In testimony whereof, I affix my signature in presence of two witnesses, on the 21st day of September, 1908.

WILLIAM LIPPS.
